INVENTOR

MICHAEL G. HOUREN,

BY *M. M. & Co.*

ATTORNEYS

UNITED STATES PATENT OFFICE.

MICHAEL GEORGE HOUREN, OF CHICAGO, ILLINOIS.

WINDOW.

1,237,045.

Specification of Letters Patent.

Patented Aug. 14, 1917.

Application filed October 21, 1915. Serial No. 57,131.

To all whom it may concern:

Be it known that I, MICHAEL GEORGE HOUREN, a citizen of the United States, and a resident of Chicago, in the county of Cook and State of Illinois, have invented certain new and useful Improvements in Windows, of which the following is a specification.

My invention is an improvement in windows, and the invention has for its object to provide a window especially adapted for street cars and the like, for the use of motor-men, and wherein the window is mounted to rotate and means is provided for rotating it, while cleaning means engages the window at its opposite faces, to thoroughly clean the same from steam, snow, rain and the like while the window is being rotated, and wherein the cleaning mechanism is hidden from view.

20 In the drawings:

Figure 1 is a front view of the improved window;

Fig. 2 is a section on the line 2—2 of Fig. 1;

25 Fig. 3 is a section on the line 3—3 of Fig. 2, looking in the direction of the arrows adjacent to the line, and

Fig. 4 is a perspective view of one of the frames.

30 As is known, on cars wherein the motor-man rides within the car, and watches the track through the window, it is difficult to keep the window free from rain, steam, snow, frost and the like that impede the view, and the present invention is designed to provide a window that may be cleaned and freed from accretions of every character by merely rotating the window in its casing.

35 The window as shown is circular, comprising a circular frame 1 having a rabbet 2 in one face for receiving a sheet 3 of glass or other transparent material, and the sheet is held in place by a molding 4 fitting in the rabbet.

40 The frame has an annular peripheral groove 5, and a belt 6 engages the groove, the belt extending to suitable operating mechanism capable of being operated manually or by power to rotate the window.

45 The window frame or casing is also provided in its opposite faces with annular

grooves 7, the said grooves being in register, and these grooves are designed to receive annular tongues 8 on the casing frames or supporting frames 9, the said frames 55 being circular as shown, and being secured to the walls 10 of the car by means of screws or nails 11.

The window proper is mounted between the walls of the car with the tongues 8 in 60 the grooves 7, and a series of balls 12 is arranged in the bottom of each groove between the tongue and the groove.

Each of the casing frames 9 is provided with a pair of parallel laterally spaced radial 65 arms 13, the said arms extending inwardly toward the center of the frame, and the free ends of the arms are offset inwardly with respect to the adjacent casing frame, toward the window proper.

70 Each of these arms 13 of each frame supports a strip 14 of cleaning material, as for instance, rubber, and the inner edge of each of the strips 14 engages the adjacent face of the sheet 3, from the center of the 75 sheet to its peripheral edge, and in such manner that when the window is rotated in its support, the rubber strips will bear against the opposite faces of the sheet, and will clean the same and free them from any 80 accretions that may have collected thereon.

The arms or standards 13 are secured to the frames 9, and the engaging edge of each strip is shaped to fit the inner surface of the sash frame 1.

85 It will be noticed that the openings 15 through the walls 10 are semicircular and they are in register, the arrangement being such that only half of the glass sheet 3 is exposed to view, namely the upper half.

90 The belt 6 may if desired be connected to a wheel or pulley driven by the motor, so that the sash will be continuously driven, or it may be rotated at predetermined intervals or at will, as may be desired.

95 I claim:

A window comprising a circular frame and a sheet of transparent material held in the frame, circular supporting frames at the opposite faces of the window, the frame 100 having annular grooves in its opposite faces, and the supporting frames having annular

tongues engaging the grooves, each supporting frame carrying a pair of radial standards extending inwardly to the center of the frame, a strip of cleaning material supported by each pair of standards and adapted to engage the adjacent face of the transparent sheet to clean the same when the window

is rotated, and means for rotating the window.

MICHAEL GEORGE HOUREN.
